UNITED STATES PATENT OFFICE.

ANDREW RUMPLER, OF CUDAHY, WISCONSIN.

BUILDING WALL.

Application filed October 23, 1924. Serial No. 745,381.

To all whom it may concern:

Be it known that I, ANDREW RUMPLER, a citizen of the United States, residing at Cudahy, county of Milwaukee, and State of Wisconsin, have invented new and useful Improvements in Building Walls, of which the following is a specification.

My invention relates to improvements in building walls.

10 The object of my invention is to provide means for constructing inexpensive and durable heat retaining walls for buildings.

More particularly stated, it is my object to provide means for utilizing natural soils, 15 such as are to be found in most localities, for forming an enclosed solid block of earth between protecting walls which prevent disintegration and co-operate with said block in forming dead air spaces which, with said 20 block, constitute high efficiency heat insulators. Also to provide means whereby temporary walls and portions of the permanent walls which enclose said block may be made to reinforce each other and to support the 25 block initially while moisture is still present therein.

In the drawings:

Figure 1 is a fragmentary view, in perspective, of my improved wall, showing the 30 same in process of erection.

Figure 2 is a horizontal sectional view of the same.

Figure 3 is a vertical section on line 3—3 of Figure 2, showing a modification.

35 Like parts are identified by the same reference characters throughout the several views.

The foundation 1 may be of any ordinary 40 construction. It is illustrated as a concrete wall. A flat wooden slab or plank 2 is placed horizontally on top of the foundation 1 and pairs of studs 3 and 4 are placed in an upright position on each side of the plank 2, preferably with their flat or wider faces 45 parallel to each other and to the planes of the edge margins of said plank 2. These studs 3 and 4 are connected at intervals by bolts 6 which pass through spacing sleeves 7. The length of each spacing sleeve is 50 substantially equal to the width of the plank 2. The ends of the floor joists 9 preferably rest on the planks 2 and, if desired, the ends of these joists may be mortised to receive the planks as shown in Figure 1.

55 The studs 3 and 4 form a frame to which sheeting boards 10 are applied and tempo-

rarily secured to the associated studs, either by nails 11 or any other suitable means, thereby forming a mold of suitable depth to receive the first filling course, or layer of 60 filling material now to be described. To form this layer the space between the sheeting boards and studs is filled with a mass of earth 13, sufficiently moist to allow it to be tamped or compressed in said space. Clay 65 containing considerable humus, such as is usually found in surface soils, is most suitable for my purpose. It will be understood, however, that the earth or earthy material selected for this purpose must contain clay 70 humus or other material of such character as to constitute a binder for the mass to prevent the resulting filler block from crumbling or falling away, when dry, as would be the case with sand unsupported by a binder. 75

I have found that I can most conveniently erect a wall by following the method hereinafter described. I first set my forms upon the studding and above the foundation wall or sill. I then take dirt from the excavation 80 and fill the space between the forms. It is difficult, however, to tamp wet earth, since the soil adheres to the tamping tool. Accordingly, when the form is almost filled with wet earth I place a layer of a few 85 inches of dry earth thereon and tamp upon the dry earth to solidify the entire mass. The dry earth will take much moisture from the wet earth beneath it, but it in turn is treated with water in order to ensure that 90 it may be compacted into a solid mass. The earth need not be perfectly dry in order to be self sustaining, and, consequently, it is possible to lay course upon course with each successive layer of wet earth placed above 95 a similar layer which is still wet. In this way a perfect bonding of the layers is ensured and the entire mass of material in any given wall space comprises a solid mass. In order to maintain the studs properly positioned during the tamping operation, I have found it expedient to brace them by means of the diagonal strips illustrated in Figure 1, so that each oppositely disposed pair of studs comprises in effect a girder, the cross 100 brace being embedded in the filling material. 105

As the material dries, it shrinks away from the studs and from the sheeting boards. The latter may then be removed and reattached to the studs at a higher level, preparatory to filling in and packing the next course of earth on top of the first course, 110

laid as above described. As soon as the sheeting boards have been removed from their original positions, inner and outer facing walls are substituted. In the drawings, 5 the inner wall is formed by first applying lath 15 to the studs and then applying one or more coats of plaster 16 thereto in the ordinary manner. The outer wall may be similarly formed, with stucco substituted for 10 the plaster, but it will of course be understood that the outer wall may be composed of any suitable material, i. e., wood, stucco, brick, or any other material suitable for constructing outer facing surfaces.

15 The operation is then repeated to form the next course in the wall of the building, strips or bars 20 being employed as fillers to prevent the moist earth forming the second course from being pressed downwardly 20 between the sheeting boards 10 and the contracted slab or block of dry earth filling previously formed. These filler strips or bars 20 may, if desired, be left in position or they may be attached to the lower sheeting board 25 10 and removed with it.

It will of course be understood that window and door openings will be provided in any well known manner familiar to builders skilled in the art to which this invention 30 pertains. When the wall is completed, there will be an outer layer of stucco or other weatherproof facing material. This will be supported by lath or by any other desired means, dependent of course on whether stuc- 35 co, brick, or other material is used for the exterior facing wall. Between this wall and the earth block or filler there will be an air space, formed by the shrinking of the earth block when drying.

40 The earth block or filler must be of sufficient thickness to be substantially self sustaining, although it will of course receive some support from the cross bolts and spacer bars which connect the studs. When dry, 45 this filler is a much better heat insulator than any solid brick or concrete wall would be if similarly placed. It will be unaffected by frost, and will retain its shape permanently if kept in a dry condition. On the 50 inner side, another air space will be interposed between the earth filler block and the lath and plaster facing, or any other suitable facing which constitutes the interior face of the wall.

55 It will be of course be understood that the planking 2 is of less width than the foundation 1, whereby the studs may rest directly upon the foundation. This planking is not an essential feature of my invention 60 but it is desirable for the reason that it serves as a spacer for the lower ends of the studs and as a support whereby the ends of

the joists are supported out of contact with the foundation.

Where my improved wall is to be used as 65 a part of a stable, a covering 21 of sheet metal may be applied to the studs and over the top of the wall, thereby not only excluding moisture more effectually but also making the structure vermin-proof. The 70 exterior facing walls protect the metal covering and therefore very thin metal sheets may be used. The metal forms a sheet metal liner for the facing wall 16 with which it is associated in Figure 3. 75

I claim:

1. A building wall comprising a filler block composed of self sustained adherent dry earth and spaced inner and outer walls having connections with each other extending through said filler block, said inner and outer walls being spaced from the filler block at a distance therefrom substantially equal to the difference in the thickness of the filler block when dry and its thickness when sufficiently wet to be tamped. 80

2. A building wall comprising inner and outer frame members connected with each other in spaced relation, inner and outer wall members secured to the frame members, and an intermediate solid block of self sustaining adherent dry earth spaced from the inner and outer wall members and from the frame members at a distance substantially equal to the shrinkage of the filler block when changing from a moist to a dry condition. 90

3. A building wall having a frame composed of inner and outer studs, spacing devices between said studs, bolts connecting the inner and outer studs in pairs, facing walls applied to the inner and outer studs respectively, and a filler block of earth interposed between said facing walls and spaced therefrom and from the studs. 100

4. A building wall having inner and outer facings in combination with a solid block of molded and adherent dry earth interposed between the facings with air spaces between it and said facings, said filler block being composed of earth containing a binder adapted, when the block is dry, to prevent disintegration, and said block being of sufficient thickness to be self sustaining. 110

5. A building wall having a frame composed of inner and outer studs, spacing devices between said studs, bolts connecting the inner and outer studs in pairs, facing walls applied to the inner and outer studs respectively, a sheet metal liner for one of the walls, and a filler block of earth interposed between said facing walls and spaced therefrom and from the studs. 115

ANDREW RUMPLER.
